UNITED STATES PATENT OFFICE.

GEORGE BINET DOREY, OF MONTREAL, QUEBEC, CANADA, ASSIGNOR TO RODGER
BALLAST CAR COMPANY, OF CHICAGO, ILLINOIS, A CORPORATION OF MAINE.

CAR CONSTRUCTION.

1,275,540.

Specification of Letters Patent. Patented Aug. 13, 1918.

Application filed June 4, 1914. Serial No. 842,922.

To all whom it may concern:

Be it known that I, GEORGE BINET DOREY, a subject of the King of Great Britain, residing in the city of Montreal, Province of Quebec, Canada, have invented certain new and useful Improvements in Car Constructions; and I do hereby declare that the following is a full, clear, and exact description of the same.

10 This invention relates particularly to cars adapted to have a plow passed therethrough and known as "ballast" cars and has for an object to improve the general construction of cars of this type.

15 The specific objects of the invention are to improve the stake construction and the connection between the stake and car.

The above with further objects and advantages will be hereinafter more fully described and particularly pointed out in the claims.

20 For full comprehension, however, of my invention reference should be had to the accompanying drawings forming a part of this specification in which similar reference characters indicate the same parts and wherein;

Figure 1 is a plan view partly broken away of a portion of the underframe, the stakes being in horizontal section;

30 Fig. 2 is a vertical section on line 2—2 Fig. 1;

Fig. 3 is a view illustrating one half of the car in end elevation, partly broken away, and half in transverse section;

35 Fig. 4 is a detail perspective view of the bolster stake connection looking inwardly at one side of the stake;

Fig. 5 is a similar view to Fig. 4 looking outwardly and toward the opposite side of 40 the stake; and

Fig. 6 is a detail transverse vertical section taken at one side of and looking toward one of the stakes.

Fig. 7 is a plan view of a corner of the 45 car, partly broken away to illustrate in horizontal section the corner stake construction shown in Fig. 1, the section being taken approximately on line 7—7 Fig. 2.

The underframe of my improved car comprises as usual a center sill 2, end sills 3, side sills 4, bolsters 5 with top plates 6, cross-beams 7 with top plates 7a.

The floor which is supported by the bolsters, cross-beams, etc., includes a permanent middle section 9 bordered at each side 55 by a Z-bar 10, the top flange of which extends outwardly from the floor preferably level with the latter to form a part of the same. The middle section of the floor is spaced from the sides of the car and such 60 floor also includes convertible side floor sections 11 extending between the bolsters and cross-beams and forming a continuation of the floor to the sides of the car, such convertible sections being hinged to the permanent floor and adapted to assume a downwardly inclined position and form, with fixed portions 12, discharge aprons as shown in Fig. 6, the novel construction of the permanent and convertible floor sections herein shown not forming a part of my invention but is included and claimed in U. S. patent application Serial No. 842,900, Yost, filed June 4, 1914.

A plow in passing through the car is 75 guided by the stakes and as a consequence the latter are subjected to considerable strains both transversely and longitudinally of the car and the construction to be now described enables the stakes to withstand 80 such strains in a thoroughly efficient manner.

In the preferred form the stakes 20 which are intermediate the corner stakes are each of channel cross-section facing longitudinally of the car, resting upon the bottom 85 flange of the side sill 4. The inner flange of each stake 20 is secured to the side sill and to one of the cross-beams or bolsters while the lower end of the stake is further secured to the side sill by a horizontal gusset 21 preferably formed integral with the stake and riveted to the lower flange of the sill to prevent twisting of the former. An upwardly tapered vertical gusset 22 extends in the longitudinal line of the car beyond 90

the sides of the stake and is located between the latter and the side sill and cross-beam and riveted to the same while a transverse vertical stake brace or gusset 23 preferably at right angles to the longitudinally disposed gusset is secured to the stake and extends, below the top level of the beam or bolster, inwardly through such gusset, which is slotted as at 24 for the purpose, into a

slot 7^b in the top plate of the cross-beam or bolster, to the diaphragm of which latter the brace is riveted as at 25 and continues above the cross-beam to the Z-bar 10. The 5 inward extension of the gusset 23 is rigidly secured to the cross-beam or bolster at one side by means of an angle brace 26. Top and bottom flanges 27 and 28 respectively, extend from the opposite side of the brace 10 23, the bottom flange being secured to the top plate of the cross-beam or bolster and the top flange to the horizontal portion 29 of a combined wear and rub plate consisting of an angular member having the rub plate 15 portion 30 secured to and extending a suitable distance up the inner flange of the channel stake and the horizontal wear plate portion 29 extending between the stake and Z-bar 10 on a level with the top flange of 20 the latter. The inner ends of the wear plate 29 and the flange 27 are extended beneath and secured to the overhanging edge of the floor constituted by the top flange of the Z-bar 10 and depressed as at 31 to accommodate 25 the latter. An angle iron bracket 32 extends from the lower end of the stake to the top of the rub plate portion 30, one flange of such bracket being secured to the closed side of the stake and extending over 30 the stake brace 23 and the other flange being secured to the outer side of the vertical gusset and the rub plate 30.

The bolsters differ from the cross-beams in that they are formed of two oppositely 35 facing channel beams spaced from each other and in the construction shown a stub stake is located at each of the ends of the bolsters and constructed in a similar manner to the cross-beam stakes with the exception 40 that the wear plate 29^a of each bolster stake is separate from the rub plate 30^a and of increased width to extend fully across the bolster, the stake brace being secured to the diaphragm of one beam and supporting one 45 side of the wear plate. The opposite side of the wear plate is supported by a box extending longitudinally of the bolster, the bottom 33 of the box being secured to the top plate 6 and the top 34 secured to the 50 wear plate and the Z-bar 10. The longitudinally disposed gusset of the bolster stake is extended as at 35 across the end of the bolster to which latter and the side sill it is secured, such gusset plate extending above 55 the bolster and being fastened to the outer end 36 of the wear plate supporting box and to the wear plate by a flange 37^a which extends inwardly from the gusset beneath the wear plate. 60 The corner stakes each consists of two channel members 38 and 39 at right angles to each other, one of which 38 faces longitudinally of the car and away from the adjacent end of the latter and has a horizontal 65 gusset 38^a which with the inner flange of

the channel member is secured to the side sill. The other channel member 39 faces outwardly from the car and is located between and its side flanges respectively secured to the member 38 and the end sill, 70 which latter is extended as at 40 for this purpose. This construction insures the maximum stiffness for the corner stakes as the member 38 efficiently withstands strains transversely of the car and the member 39 75 longitudinal strains while a thoroughly rigid connection is obtained by securing one of the flanges of the latter member to the end sill and the other to the stake brace which is in turn secured to the under-frame. The channel member 39 is secured at the bottom to the side sill by means of a bottom flange 41 and to a transverse angle plate 15 by an angle bracket 42, such plate 15 being carried by the inside of the end 80 sill.

A corner stake brace or gusset 43 is located between the members 38 and 39 and extends from the outer edge of the former inwardly to the Z-bar 10 and has a bottom 90 flange 44 extending toward the end sill, over and secured to the plate 15 while a top flange 45 of the brace extends in the opposite direction away from the end sill and supports a wear plate 46 secured thereto on a level with the floor. The inner ends of the flange 45 and wear plate 46 are depressed to fit under and accommodate the overhanging edge of the floor constituted by the top flange of the Z-bar 10 to which 100 latter the wear plate and flange are secured.

A vertical gusset 47 disposed longitudinally of the car is secured to the side sill at the bottom and extends up and is secured to the member 38 between the same and 105 the sill, one edge of such gusset abutting against the stake brace 43.

As the inner ends of the stake braces are overhung by the flooring of the car the stakes will be thoroughly braced against 110 damaging pressure and this bracing is proportionately augmented by the weight of the plow when the latter passes over and bears upon the flooring and the inward extensions of the stake braces. The integral 115 formation of the rub and wear plates of the cross-beam stakes further increases their rigidity and resistance to damaging pressure and also constitutes horizontal gussets to prevent twisting of the stakes.

Each end stake is beveled to present a flared opening at the end of the car so that the entrance of the plow to the latter can be readily effected and this bevel is secured by pressing the member 39 above the floor level as at 48. A rub plate 49 of suitable height is secured to the stake while in order to further facilitate the entrance of a plow a roller 50 is vertically mounted just above the floor level upon each corner stake by 130

bearing plates 51 carried by the outer side of the stakes, the rollers extending through apertures 52 in the latter and protruding from the inner surface of the same, thus providing a bearing surface which changes as the roller moves and so avoids excessive wear at any one point.

What I claim is as follows:

1. In a ballast car, the combination with 10 the underframe, of a stake and means for securing the stake to the underframe including a brace secured to the stake and extending inwardly therefrom over the underframe, the inner extension of the brace being 15 secured to the underframe and a wear plate secured upon the top of such inward extension.

2. In a ballast car, the combination with 20 the underframe, a floor upon the underframe and spaced from the sides of the latter, of a stake and means for securing the stake to the underframe including a brace secured to the stake and extending inwardly 25 therefrom over the underframe and under the side edge of the floor, such brace having top and bottom flanges, the latter being secured to the underframe and a wear plate secured to the top flange and extending between the stake and floor.

3. In a ballast car, the combination with 30 the underframe and a floor spaced from the sides of the car and having an outwardly extending flange, of a stake and means for securing the stake to the underframe, including a brace secured near its outer end to the stake and extending at its inner end under the flange.

4. In a ballast car, the combination with 40 the underframe and a floor spaced from the sides of the car, of a stake and means for securing the stake including a brace secured near its outer end to the stake and secured at its inner end to both the underframe and floor.

5. In a ballast car, the combination with 45 the underframe including a cross-beam and a side sill, of a stake secured at the bottom to the side sill, a horizontal gusset secured to and extending between the stake and side 50 sill, a vertical gusset secured to and located between the stake and side sill in the longitudinal line of the car, such gusset having a slot therethrough, a transverse vertical gusset secured to the stake, passing through 55 said slot and secured to the cross-beam, and a reinforcing plate secured to the inside of the stake and bent inwardly therefrom along the top of and secured to the transverse vertical gusset.

6. In a ballast car, the combination with 60 the underframe including a cross-beam and a side sill, of a stake secured at the bottom to the side sill, a vertical gusset secured to and located between the stake and side sill 65 in the longitudinal line of the car, such

gusset having a slot therethrough, and a transverse vertical gusset secured to the stake, passing through said slot and secured to the diaphragm of the cross-beam.

7. In a ballast car, the combination with 70 the underframe including a bolster and a side sill, of a stake secured at the bottom to the side sill, a vertical gusset secured to and located between the stake and side sill in the longitudinal line of the car, such gusset 75 being extended above the bolster, having a slot therethrough and presenting an inwardly extending flange at the top, a transverse vertical gusset secured to the stake, passing through said slot and secured to the 80 top and near one side of the bolster, a box secured to the top of the bolster near the other side and fastened to the longitudinal vertical gusset and a wear plate extending over and secured to the transverse gusset 85 and box and to the flange of the longitudinal vertical gusset.

8. In a ballast car, the combination with 90 the underframe, including an end sill and a side sill, of a corner stake comprising a channel member facing longitudinally of the car and secured to the side sill and a second channel member facing outwardly from the car, located between and having its flanges 95 respectively secured to the longitudinally facing channel member and end sill.

9. In a ballast car, the combination with 100 the underframe including a side sill, an end sill, a lower plate secured to the underside of and extending longitudinally of the end sill and an upper plate secured to the inside of and extending longitudinally of the end sill, of a corner stake comprising a channel member secured to the side sill and facing longitudinally of the car, a horizontal gusset extending between the channel member and the side sill, a second channel member secured to the side sill and facing outwardly from the car, such outwardly facing member 105 being located between and having its flanges respectively secured to the longitudinally facing member and the end sill, an angular bracket having one flange extending along the inside of and secured to the channel members and the other flange secured to 110 said lower plate and a transverse stake brace located between the channel members and extending inwardly along and being secured to said upper plate.

10. In a ballast car, a corner stake having 115 an inner beveled surface with an aperture therein and a roller mounted upon the stake and projecting through said aperture.

11. In a ballast car, a stake and means for 120 fastening the stake including two gusset plates, one of which passes through the other.

12. In a ballast car, the combination with 125 the underframe including a cross beam and a side sill, of a stake secured at the bottom 130

to the side sill, a vertical gusset secured to and located between the stake and side sill in the longitudinal line of the car, such gusset having a slot therethrough, and a transverse vertical gusset secured to the stake passing through said slot and secured to the cross-beam.

13. In a ballast car, the combination with the underframe, including a cross-beam, of
10 a stake, a vertical gusset secured to and located between the stake and cross-beam in the longitudinal line of the car, such gusset having a slot therethrough and a transverse vertical gusset secured to the stake
15 passing through said slot and secured to the cross-beam.

14. In a ballast car, the combination with

the underframe including a cross-beam and a side sill, of a stake secured to the side sill, a horizontal gusset secured to and extending between the stake and side sill, a vertical gusset secured to and located between the stake and side sill in the longitudinal line of the car, such gusset having a slot therethrough and a transverse vertical gusset secured to the stake, passing through said slot and secured to the cross-beam.
